HAMMERMILL

Ernest F. Boger, 9018 37th SW,
Seattle, Wash. 98126

Filed Oct. 14, 1970, Ser. No. 25,487

Term of patent 14 years

Int. Cl. D15—99

U.S. Cl. D55—1

FIG. 1

FIG. 2

FIG. 4₁

FIG. 3

FIG. 1 is an overall perspective of a hammermill embodying my new design;

FIG. 2 is a plan view thereof;

FIG. 3 is a side elevational view thereof;

FIG. 4 is an end elevational view thereof.

I claim:

The ornamental design for a hammermill, substantially as shown and described.
